(57) **CLAIM**

We claim the ornamental design for a user interface in an analyte meter, as shown and described.

DESCRIPTION

FIG. 1 is a perspective view of the front of a user interface in an analyte test meter, as seen from one perspective;

FIG. 2 is a perspective view of the front of the user interface in the analyte test meter, as seen from another perspective;

FIG. 3 is a top plan view thereof;

FIG. 4 is a front elevational view thereof;

FIG. 5 is a rear elevational view thereof;

FIG. 6 is a first side view thereof;

FIG. 7 is a second side view thereof; and,

FIG. 8 is a bottom plan view thereof.

The feature shown in broken lines in various Figures are for illustrating reference or environmental structure.
